JOHN ALFONS NOVAK, OF EAST CHICAGO, INDIANA, ASSIGNOR OF ONE-FOURTH TO
JOSEPH ZIELINSKI, OF EAST CHICAGO, INDIANA.

WINDMILL-PUMP.

1,317,815.

Specification of Letters Patent.

Patented Oct. 7, 1919.

Application filed April 22, 1919. Serial No. 291,870.

To all whom it may concern:

Be it known that I, JOHN ALFONS NOVAK, a citizen of Poland, residing at East Chicago, county of Lake, and State of Indiana, have invented certain new and useful Improvements in Windmill-Pumps, of which the following is a specification.

This invention relates to improvements in devices for raising water from wells by means of the wind, and has as its principal object the provision of means adapted to be engaged upon the roof of a relatively high building, and which are operated by the velocity of the wind currents in such manner as to actuate a double barreled pump whereby a continuous stream of water may be secured.

A further object is to so arrange the mechanism of the pump connection that it will automatically actuate the pump pistons alternately.

These and other like objects, which will become more fully apparent as the description progresses, are attained by the novel construction and combination of parts hereinafter described and shown in the accompanying drawings, forming a material part of this disclosure, and in which—

Figure 1 is a partial side elevation and partial vertical sectional view showing a combined windmill and pump made in accordance with the invention.

Fig. 2 is a transverse sectional view taken on line 2—2 of Fig. 1.

Fig. 3 is a fragmentary vertical view taken on line 3—3 of Fig. 2, and

Fig. 4 is a fragmentary sectional view showing the means by which the pump may be connected or disconnected at will.

Referring to the drawings, the numeral 10 indicates the peak of the roof of a conventional type of building, and which has secured upon it a bracket 11, having an annular flange 12, corresponding to an upper flange 14, formed with the upper portion of the structure, there being interposed between the flanges a plurality of balls 15, so that the flanges can easily rotate.

Extending up from the flange 14, is a hollow standard 17, formed with a rectangular head 18, on one side of which is attached a steering or wind vane 20, so that a propeller 21 may be properly positioned to receive the full force of the wind.

The propeller 21 is mounted upon a short

horizontal shaft 22, carried in the brackets 23, extending from the hollow head 18, the inner end of the shaft having upon it a miter gear 24, meshing with a similar gear 25, having an extending hub 26, containing an annular groove 27, in which is received the curved yoke elements 28, of a lever 29 pivoted on a pin 30, on a projection 31 extending from the bracket 23.

Attached to the lever 28 is a pull cord 32 by which the lever may be drawn down against the effect of the spring 33, one end of which abuts against the lower end of the hub 26 and the other within the hollow head 18, thereby providing means whereby the gears may be connected or disconnected at will.

The gear 25 is secured by a key 35 to a vertical shaft 36, housed in suitable bearings formed in standards 17 and passing down through the roof, the lower end of the shaft extending into a mechanism casing 38 in which it is guided, and terminates in a worm 40, meshing with a worm gear 41, fixed upon a horizontal shaft 42, housed in the mechanism casing 38.

Also secured upon the shaft 42, near its ends, are a pair of bevel gears 44, and 44', thus when the wind is blowing and the gears 24 and 25 are in mesh, the bevel gears 44 and 44' are continually rotated. A pair of beveled, internal, endless racks 45 and 45' are engageable with the teeth of the pinions 44 and 44', these racks being supported by vertical shafts 46 and 46' in the casing 38 in such manner as to slide therein, and which will also rotate, due to the following causes.

When the end of one of the racks rises to its full limit it makes contact with one or the other of a pair of fingers 47 and 47', these fingers having a beveled lower surface and extending into the casing with which they are rigidly engaged, so that when the beveled rack end comes in contact with the bevel surface of the finger, the rack is caused to oscillate so as to engage the bevel gear upon the opposite side, the rack being held ordinarily in engagement with the teeth of the rack, by pins 50 and 50' extending laterally outward from their ends and engageable within parallel grooves 52 and 52', the pins being arranged both at the top and bottom of the sliding rack, and the slots being connected arcuately at the top and bottom, so that at no time do the pins pass out

from the slots, but are diverted so as to travel circuitously, in an obvious manner.

The lower end of the casing is connected to a bracket 55 by means of bolts 56, having between them a pair of cylinders 58 and 58', in which operate piston valves 59 and 59', these piston valves being attached to the piston rods 60 and 60', extending downward from the racks opposite to the rods 46 and 46'.

Engaged in the brackets 55 is a pipe 61 connected with a wall, cistern, or other supply of water, the discharge taking place through the pipe 62 adjacent to the valves 63 and 63' operating within the water space 64.

In operation, the gears 24 and 25 being in mesh, rotary motion is transmitted by the shaft 36 to the transverse shaft 42, causing one of the bevel gears 44 engaged with one side of the rack 45 to move the rack and plunger downward, while the opposite pinion 44', engaged upon the opposite side of the other rack, causes the same to move upward, thus actuating the valve pistons 49 and 49' in opposite directions, the upper movement of the piston 59 opening the valve 65, while the downward movement of the piston closes the valve, forcing the water upward through it, past the valve 63 and into the discharge pipe 62.

Similarly when the rack has reached the extent of its limit, it is switched over by par-

tially rotating the rods 46 and 46' whereupon it is moved upward and the alternate piston is caused to descend.

35

From the foregoing it will be seen that a novel device for operating a pump in connection with a windmill has been disclosed in which the mechanical movements are actuated automatically and in such manner as to provide a constant stream of water.

40

Having thus described my invention what I claim as new and desire to secure by Letters Patent, is—

In a windmill of the character described, 45 the combination with a mechanism casing of a horizontal shaft, a pair of bevel gears secured near the ends of said shaft, a worm in the center of said shaft adapted to mesh with a worm on the windmill operating 50 shaft, a pair of endless racks in mesh with the teeth of said bevel gears, a pair of fingers having a beveled surface secured to and extending into said casing and engaging with said racks at the limit of their upward 55 movement, and pins at the top and bottom of the sliding racks extending into parallel grooves, piston valves having their rods secured to said racks, substantially as described and for the purpose set forth. 60

In testimony whereof I have affixed my signature.

JOHN ALFONS NOVAK.
